Application November 2, 1948, Serial No. 57,862

3 Claims. (Cl. 242—55.4)

1

This invention relates to a magazine display and dispensing rack for rolled goods, and more particularly to the type of rack in which a plurality of rolls of goods are supported, such as that disclosed in U. S. Patent No. 919,725 issued to J. G. Huffman April 27, 1909, and the rack disclosed in U. S. Patent No. 1,009,827 issued to J. D. Chambers November 28, 1911.

The primary object of the invention is to facilitate the handling of rolls or rug material such as linoleum, and to enable the material to be advantageously displayed so that a pattern may be easily selected by a customer.

Another object is to facilitate the dispensing of a length of the rolled material displayed in the rack, and to enable the vendor easily and quickly to measure from the supply roll the desired length of material, and sever it from the supply roll by employing a circular knife substantially in the type disclosed in U. S. Patent No. 1,589,207 issued June 15, 1926 to J. E. Miller.

A further object of the invention is to roll the severed length of material so that it may be readily tied in rolled condition and released from the rolling equipment into a suitable delivery trough from which it may be conveniently removed and delivered to the customer.

The above and other objects may be attained by employing this invention which embodies among its features a pair of winding tubes mounted adjacent opposite ends of a magazine display and dispensing rack of the type above referred to, to move along an axis which lies parallel to the axis of the roll of goods in the rack, each tube having a goods receiving slot extending longitudinally therewith from one end, and means to rotate said tubes in unison about the axis along which they move longitudinally.

Other features include a clamp within each tube adjacent the slot therein to clamp the goods against the tube and securely hold it during the rolling operation, and means to rotate the tubes in unison about the axis along which they move longitudinally.

Still other features include a receiving trough carried by the rack adjacent each winding tube to receive the goods rolled on the tubes after the tubes have been withdrawn from the interior of the rolled goods.

In the drawings:

Figure 1 is a top plan view of a magazine display and dispensing rack for rolled goods embodying the features of this invention.

Figure 2 is a front view in elevation of the rack illustrated in Figure 1.

2

Figure 3 is an end view of the rack illustrated in Figure 1.

Figure 4 is an enlarged transverse sectional view taken substantially along the line 4—4 of Figure 1.

Figure 5 is a perspective view of one of the roll supporting and display cradles.

Figure 6 is an enlarged fragmentary front view partially in section illustrating in detail the construction of one of the goods rolling tubes.

Figure 7 is a transverse sectional view on an enlarged scale taken substantially along the line 7—7 of Figure 6.

Figure 8 is a longitudinal sectional view taken substantially along the line 8—8 of Figure 7.

Figure 9 is a perspective view of one of the rolling tubes.

Figure 10 is a fragmentary top plan view of a portion of the rack illustrating in detail the rotary cutting knife.

Figure 11 is a fragmentary elevational view of the knife illustrated in Figure 10, and

Figure 12 is a vertical sectional view through a modified form of the invention.

Referring to the drawings in detail this improved rack comprises a pair of spaced parallel end frames each designated generally 10, and each having diagonal cross bars 12 which are provided at their intersections with openings to receive an elongated shaft 14. The top and bottom corners of the end frames 10 of the rack are joined by parallel corner bars 16 which lie parallel to the shaft 14, and cooperate with the end frames 10 in forming a supporting rack for longitudinally spaced wheels 18 which are mounted for rotation on the shaft 14 adjacent each end frame 10. One end of the shaft 14 projects through the cross bars 12 and has fixed thereto a drive sprocket 20 which has driving connection with the drive sprocket 20 of a speed reduction gearing housed within the conventional housing 22, through the medium of a drive chain.

24. A suitable drive motor 26 preferably of the reversible type has driving connection with the gearing housed in the housing 22, so that when the motor is operated, the wheels 18 may be rotated in unison with the shaft 14. Mounted in suitable brackets 28 which are fixed to the upper rear corner of each end frame 10 is a guide roller 30, and fixed to the top cross bars of the frame and extending transversely thereof to a common plane beyond the front end of the frame are angle bars 32, the forward ends of which are joined by a longitudinally extending

50 bar 34 forming the upper front corner of an

overhanging frame designated generally 36. Suitable brackets 38 are fixed adjacent opposite ends of the bar 34 and rotatably supported on said brackets is a guide roller 40 which cooperates with the roller 30 in guiding a length of goods L from a supply roll R across the top of the rack.

Mounted in suitable bearings 42 carried at peripherally spaced points by the wheels 16 are cradles designated generally 44 (Figure 5) each of which comprises a pair of parallel side bars 46 which are connected at opposite ends adjacent opposite corners of segmental frames, each of which is provided at an intermediate corner with a trunnion 50 which is received in a bearing 42 so that as the wheels rotate, the cradles 44 will revolve about the axes of the trunnions, and remain at all times suspended from the wheel. Extending transversely at spaced intervals between the longitudinal bars 46 of each cradle 44 are cross bars 52 which are arcuate in shape to correspond to the bottom bars of the segmental frames 48, and journaled in the bars 52 and the bottom bars of the planes 48 are supporting rollers 54 upon which the supply rolls R of the rolled goods are supported. Extending upwardly from the rear corner of each frame 10 adjacent the guide roller 30 is a bracket 56, and supported by the brackets 56 in parallel spaced relation above the roller 30 are spaced parallel track rails 58 on which a carriage 60 is mounted to slide longitudinally in parallel relation to the roller. A suitable shaft 62 extends laterally from the carriage 60 in the direction of the roller 30 and mounted for rotation on the shaft 62 is a cutting wheel 64 which moves longitudinally across the top of the bar 16 adjacent the roller 30 so that its cutting edge will engage the length L of goods extending across the top of the rack, and sever it from the supply of goods in the roll R as the carriage 60 is moved longitudinally of the track rails 58 manually by a suitable handle 66.

Mounted in the overhanging frame 36 at the forward end of the rack about an axis which lies parallel with the axis of the shaft 14 is a drive shaft 68 to which is fixed adjacent each end a spur gear 70, and fixed to one end of the drive shaft 68 is a hand crank 72, by which the shaft may be rotated. Carried by the frame 36 adjacent each end thereof and below the shaft 68 are suitable bearing sleeves 74, and pivotally supported in a suitable bracket 76 adjacent the outer end of each bearing sleeve 74 is a latch arm 78 carrying a hook 80 which overhangs the end of its respective bearing sleeve and is urged toward the axis thereof under the influence of a suitable spring 82. Mounted for rotation in each bearing sleeve, and for longitudinal sliding movement therein is a winding tube 84 to one end of which is keyed or otherwise secured as at 86 a drive pinion 88. The hub 90 of the drive pinion 88 is provided with an annular groove 92 in which the hook 80 is received when the tube is pushed inwardly toward the center of the machine, and the pinion 88 is in mesh with the drive pinion 70, as will be readily understood upon reference to Figure 6. It will thus be seen that when the hand crank 72 is rotated, and the pinions 88 are in mesh with the pinions 70, the tubes 74 will be rotated in unison. Entering the end of each tube 84 remote from its respective drive pinion 88 is an incision 94, the inner end of which joins a relatively short transversely extending incision 96, and the portion of the tube 84 between the incisions 94 and 96 is bent inwardly as at 98 to

form a slot in the tube in which the goods to be wound is received.

Fixed within each tube adjacent the slot therein is a bearing bracket 100 having an opening 102 therein which aligns with an opening 104 formed in a bearing bracket 106 which is fixed within the tube 84 adjacent the end carrying the pinion 88 and mounted to rock in the openings 102 and 104 is a rock shaft 108. A clamping cam 110 is fixed to the shaft 108 adjacent the slot in the tube 84 for bearing on the goods to be wound and clamping it against the wall of the tube and fixed to the end of the shaft adjacent the bearing bracket 106 is a hand lever 112 by which the shaft 108 may be rocked to move the clamp cam 110 into and out of goods clamping position.

Suspended from the frame 36 adjacent each bearing sleeve 74 and curving forwardly beneath each tube 84 is a receiving trough 114 into which the wound length L of the goods is received when the winding tubes 84 are shifted longitudinally in their bearing sleeves 74 to withdraw them from a length of wound goods.

In operation rolls R of rolled material to be dispensed and displayed, are placed in the cradles 44 carried by the wheels 16. The customer then selects from the rolled material a pattern which he desires to purchase, and the vendor sets the motor 26 into operation to cause the wheels 16 to rotate about the shaft 14, until the selected roll of material is moved to a position substantially as shown in Figure 4. With the carriage 60 moved fully to one side or the other of the rack, as suggested in Figure 1, the material to be dispensed is led upwardly over the roll 30 and beneath the track rails 58 across the top of the machine and down over the guide roll 40 to a position such as will enable the lowermost corners of the material to be entered into the slots formed in the winding tubes 84 by the incisions 94 and 96. The hand lever 112 is then manipulated to move the eccentric clamp 110 about the axis of the shaft 108, to cause the periphery thereof to clamp the material against the inner side of its respective tube. Having clamped both corners of the material in the tubes 84, the hand crank 72 is rotated to drive the shaft 68 and cause the gears 88 carried by the tubes 74 to rotate and wind off of the roll R the desired amount of material. The carriage 60 is then moved across the machine along the track rails 58 to cause the cutter blade 64 to sever the measured length of material from the supply roll R. The hand crank 72 is again rotated, to wind the balance of the material which has been severed from the supply roll R into a compact bundle. The bundle may then be tied in rolled form by passing twine therearound at spaced points between the opposed ends of the winding tubes 84. Having wound and tied the measured length of material, the latches 78 are moved against the effort of the springs 82 to disengage the hooks 80 from the walls of the annular grooves 92 in the hubs 90 of the pinion 88, so that the winding tubes 84 may be shifted longitudinally within the supporting sleeve 74 to withdraw the opposed ends of the tubes from their positions within the rolled material. Upon extracting the tubes 84 from their respective ends of the rolled length of material, it will drop into the material receiving troughs 114 from which it is removed for delivery. After having removed the material from the troughs, the winding tubes 84 are restored to their initial positions, with the pinions 88, meshing with the drive pinions 70, and

the hooked ends 80 of the latches 78 again entering the grooves 92 in the hubs 90 of the pinions 88 ready for a repeat operation.

In the modified form of the invention illustrated in Figure 12 a frame designated generally 116 supports two vertically spaced horizontally extending shafts 118 on which are mounted for rotation adjacent opposite ends sprocket wheels 120. There is a pair of sprocket wheels adjacent each end of the frame 116, and trained over each pair of sprocket wheels is an endless chain 122 upon which are supported at spaced points cradles 124 corresponding in all respects to the cradles 44 previously described. The sprocket wheels 120 may be driven in any convenient manner as by an electric motor (not shown), and latched as at 126 to opposite ends of the frame 116 is a measuring frame designated generally 128. A suitable measuring gauge 130 of conventional form is mounted on the frame 128 through which the material from a supply roll R' mounted in one of the cradles 124 is passed as it is led across the top of the frame 128. Supported in any suitable manner at opposite ends of the frame 128, and extending longitudinally thereabove are spaced parallel track rails 132 upon which a suitable carriage 134 is mounted to slide. This carriage corresponds in all respects to the carriage 60 previously described, and supports a conventional cutting disk 136, the cutting edge of which rides along the upper forward cross bar 138 of the frame 128. Mounted for longitudinal sliding movement in a supporting sleeve 140 adjacent each end of the frame 128 immediately below the bar 138 is a winding tube 142 which corresponds in all respects to the winding tubes 84 previously described, and these winding tubes are each provided with a drive gear 144 which is adapted to mesh with a drive pinion 146 mounted adjacent an end of a transversely extending shaft 148 which corresponds in all respects to the shaft 68 previously mentioned.

In the operation of the modified form of the device rolls R' of the material to be dispensed are mounted in the cradles 124 and when material is to be severed from a selected roll R', it is led from the roll over the top of the frame 128 and through the measuring device 130, with its forward edge turning downwardly over the forward edge of the bar 138. The corners of the piece are introduced into the winding tubes 142 in the same manner as the material is entered into the winding tubes 84, and upon rotating the shaft 148 the material is wound on the tubes. When the desired amount of material has been wound from the supply roll R', the carriage 134 is moved across the frame 128 and along the bar 138 to sever the measured length of material from the supply roll. After winding the material and tying it as previously explained the winding tubes 142 are shifted longitudinally in respective sleeves 140, and the wound and tied length of material is dropped into the receiving troughs 150 which are supported on the frame 128 immediately below the winding tubes 142.

While in the foregoing there has been shown and described the preferred embodiment of this invention it is to be understood that minor changes in the details of construction, combination and arrangement of parts may be resorted to without departing from the spirit and scope of the invention as claimed.

Having described the invention, what is claimed as new is:

1. In a magazine display and dispensing rack of the type in which a plurality of rolls of goods are supported, dispensing means for rolling a predetermined length of goods selected from the goods on the rack comprising a pair of winding tubes mounted adjacent opposite ends of the rack to move longitudinally along an axis which lies parallel to the axis of a roll of goods in the rack into operative and inoperative positions, each tube having a goods receiving slot extending longitudinally thereinto from one end, and means to rotate said tubes in unison about the axis along which they move longitudinally when said tubes are in operative positions.
2. In a magazine display and dispensing rack of the type in which a plurality of rolls of goods are supported, dispensing means for rolling a predetermined length of goods selected from the goods on the rack comprising a pair of winding tubes mounted adjacent opposite ends of the rack to move longitudinally along an axis which lies parallel to the axis of a roll of goods in the rack into operative and inoperative positions, each tube having a goods receiving slot extending longitudinally thereinto from one end, a shaft mounted adjacent the tubes to rotate about an axis which lies parallel to the tubes, a drive gear on each end of the shaft, a drive pinion on each tube meshing with an adjacent drive gear and means to rotate the shaft.
3. In a magazine display and dispensing rack of the type in which a plurality of rolls of goods are supported, dispensing means for rolling a predetermined length of goods selected from the goods on the rack comprising a pair of winding tubes mounted adjacent opposite ends of the rack to move longitudinally along an axis which lies parallel to the axis of a roll of goods in the rack into operative and inoperative positions, each tube having a goods receiving slot extending longitudinally thereinto from one end, means to rotate said tubes in unison about the axis along which they move longitudinally when said tubes are in operative positions, guide rollers mounted on the rack to rotate about axes which lie parallel to the axis about which the tubes rotate and positioned on the longitudinal upper edges of the rack to guide the goods from the side of the rack remote from said tubes, across the top of said rack prior to engagement with said tubes.
